GROUNDING FITTING

Lewis H. Church, Westfield, N. J., assignor to
 The Thomas & Betts Co., Elizabeth, N. J., a
 corporation of New Jersey

Application September 24, 1937, Serial No. 165,449

4 Claims. (Cl. 173—273)

The invention relates to a grounding fitting having two members, each of which is provided with a clamping seat between which a grounded conductor is adapted to be clamped, and each of which members also provide a hinge bearing for clamping a wire to be grounded. The ground wire serves as the hinge pin for the two members to enable pivotal movement therebetween.

It is an object of the invention to construct a new and novel grounding fitting of the type having two members and in which the ground wire serves as a hinge pin between the two members so that they will have a pivotal clamping movement therebetween, and at the same time that the pivotal clamping action takes place, the grounding wire is clamped between the two members.

Another object of the invention is to construct a grounding fitting of the type having two pivotal members in which the ground wire serves as a hinge or pivot pin between the two members, and in which two operating means are provided, the second of which assures effective clamping of the ground wire.

Another object of the invention is to devise a grounding fitting of the type in which the wire to be grounded serves as a hinge pin between two clamping members which are adapted to grip a grounded conductor therebetween. The hinge bearings, which receive the ground wire, are ridged or bulged relatively to the axis thereof, so that the wire is bent when clamped between the hinge bearings and a second operating means is provided adjacent to the hinge bearings for assuring sufficient clamping action at the hinge bearings to fully and effectively bend the ground wire therebetween and to firmly clamp the ground wire.

Other objects of the invention will be more apparent from the following description taken in connection with the accompanying drawing, illustrating a preferred embodiment of the invention, in which:

Figure 1 is a longitudinal section through the grounding fitting in assembled relation and gripping a pipe, which is adapted to be grounded, and the ground wire.

Figure 2 is a plan or top view of the grounding fitting with the ground wire and ground conductor clamped therein.

Figure 3 is a side elevation of the grounding fitting viewed from the ground wire side.

Figure 4 is a bottom view of the grounding fitting also with the ground wire and pipe clamped therein.

The grounding fitting to be described herein utilizes two members, each of which is provided with a clamping seat to engage a grounded pipe or conductor and with a hinge bearing to engage a ground wire. Normally a single operating means or screw will clamp the ground wire between the hinge bearings and the grounded pipe between the clamping seats. In order to more effectively clamp the ground wire, a second operating means is provided adjacent to the hinge bearings. This second operating means becomes increasingly effective where the hinge bearings are ridged or bulged and the ground wire received therebetween is of relatively heavy gauge. Where these conditions exist, the single operating means is subjected to considerable strain in order to create sufficient clamping or compressing action upon the ground wire to effectively bend the wire into the bulged shape of the hinge bearings. At times, too, with the bulged hinge bearings effective clamping of the ground wire is difficult with a single operating means. The second operating means applies its pressure adjacent to the hinge bearings so that its full force is applied between the hinge bearings and the wire is fully bent to conform with the ridged or bulged form of the hinge bearings. The ground wire is also more firmly clamped therebetween.

The grounding fitting comprises a clamping member 10 having a clamping seat 11, which is adapted to receive a grounded conductor P, and a hinge bearing 12 which faces in an opposite direction to that of the clamping seat 11. The hinge bearing is bulged or ridged in the direction of the axis of the hinge bearing or ground wire to be received thereby. Preferably the bulge is arcuate, and that illustrated is convex. One end of the clamping member has a hole 13 for an operating means or bolt, and the other end has a threaded hole 14 for receiving a second operating means, as will be described hereinafter.

A second clamping member 18 has a clamping seat 19. Arms 20, two of which are shown, extend outwardly from the clamping seat, which arms carry a cross member 21 which provides a hinge bearing 22 for a ground wire. This hinge bearing is ridged or bulged in the direction of its axis or the axis of the ground wire to be received thereby. The bulge in both hinge bearings should conform and hence the hinge bearing 22 is arcuate and concave. This hinge bearing also faces in an opposite direction to that in which the clamping seat faces. A grounding

wire hole 29 extends through each arm 20 and the holes are tangent, or approximately so, to the surface of the hinge bearing 22. One end of the clamping member carries a slot 23 to receive an operating means, and the other end has a hole 24 through which a second operating means passes, as will be described. This clamping member also has a pair of spaced ridges 25, one being provided on each side of the slot 23, the purpose of which will appear more fully hereinafter. The spaced arms 20 and the cross member 21 provide an aperture through the clamping member.

The clamping member 18 preferably carries a socket member 26 in which there is an enlarged opening or socket 27, preferably in alignment with the grounding wire holes 29 through the arms 20, to receive the armor R on the grounding wire W. A screw 28 is threaded into the socket member 20 and projects into the socket 27 so that the screw may be tightened against the armor and effectively ground the armor to the grounding fitting and the grounded conductor or pipe P.

The hinge bearings 12 and 22 are opposed to each other so that the bearings engage diametrically opposite surfaces of the grounding wire W. The grounding wire disposed therebetween is, therefore, subjected only to compression and it is utterly impossible to shear off the grounding wire 30 under the clamping action, regardless of how great a clamping action is exerted thereagainst. As illustrated in Figure 3, the hinge bearings are ridged or bulged in the direction of their own axis, or the axis of the grounding wire to be received therebetween. One hinge bearing has a convex bulge and the other is concave in order that the wire receiving passage be uniform. It is immaterial which hinge bearing is convex and which concave. The purpose of the ridged or arcuate form of hinge bearings will be explained hereinafter.

An operating means or bolt 30 has a head 31 and a nut 32 threaded thereon. The bolt passes through the opening 13 in the end of the clamping member 10 and through the slot 23 in the end of the clamping member 18. The sides of the nut 32 are engaged by the spaced ridges 25 so that the nut will not turn when the operating means or bolt is tightened.

50 A second operating means or screw 35 has a head 36. This operating screw passes through the hole 24 in the clamping member 18 and is received in the threaded hole 14 in the clamping member 10. It will be observed that this second operating means is adjacent to the hinge bearings 12 and 22. The screw 35 not only serves as a second operating means when mounting the fitting in service position with a grounding wire and upon a grounded conductor, but also performs a second function in that when it extends through the hole 24 and is threaded in the hole 14, it retains the two clamping members together in assembled relation for shipment and when in stock.

65 The grounding fitting is assembled for shipment and use by inserting the end of the clamping member 10, carrying the hinge bearing 12, in the opening between the arms 20 of the clamping member 18 so that its hinge bearing is opposed to the hinge bearing 22. The second operating screw 35 is then inserted through the hole 24 in the clamping member 18 and threaded into the hole 14 in the clamping member 10. The two clamping members are held together by this screw. The operating bolt 30 is then inserted through the

opening 13 and the nut 32 is threaded thereupon. Assembled, as described, the grounding fitting is ready for use or stock with all parts retained together and without requiring the separation of any part in order to put the fitting into service by mounting it upon a grounded conductor and inserting a grounding wire therein.

In mounting the grounding fitting for use, the screw 35 is permitted to remain with the ends of the clamping members 10 and 18 widely separated, and the end of the grounding wire W is inserted through the socket member 26 and the holes 29 in the arms 20 so that the wire projects completely through the grounding fitting and lies between the hinge bearings 12 and 22. The grounding wire is inserted far enough through the fitting so that the armor R abuts against the end of the socket 27 in the socket member 26. The screw 28 for engaging and clamping the armor may or may not be tightened, as desired, although preferably it is not tightened at this time. The operating bolt 30 is now pulled through the hole 13 until the nut 32 engages the clamping member 10 so that the bolt does not obstruct the opening between the ends of the clamping members.

25 The clamping members 10 and 18 are now opened wide enough so that the grounded conductor or pipe P may be inserted therebetween and in engagement with the clamping seats 11 and 19. With the pipe between the seats 11 and 19, the bolt 30 is then pushed through the hole 13 until its head 31 engages the end of the clamping member 10, and the end of the bolt carrying the nut may be inserted laterally through the slot 23 in the clamping member 18 without removing the nut from the end of the bolt. Tightening of the operating bolt 30 draws the clamping seats 11 and 19 together so that the grounded conductor P is clamped therebetween, and simultaneously the hinge bearings come together and grip the grounding wire W while the two clamping members are pivoting upon the wire as a hinge pin. The grounding wire W and the grounded pipe P are, therefore, simultaneously clamped by the operating means. It will be noted that in putting the fitting to use, it is unnecessary to separate any part from the complete assembly.

30 It has been described above that tightening of the operating means bends the grounding wire into a ridged or bent form, conforming to the ridge or arcuate form of the cooperating hinge bearings 12 and 22. In order to assure complete bending of the grounding wire between the cooperating arcuate hinge bearings 12 and 22, the second operating means or screw 35 is now tightened, and because it is adjacent to the hinge bearings, tightening of this second clamping means positively assures that the grounding wire is bent fully to conform with the ridged or arcuate shape of the hinge bearings. It also assures that the grounding wire is firmly clamped between the hinge bearings.

35 The forming of a ridge or arc in the grounding wire W assures a firmer grip upon the wire. It is apparent that if straight hinge bearings were provided, a longitudinal pull upon the grounding wire would merely have to overcome the frictional engagement of the hinge bearings upon the grounding wire. With the ridge or arcuate bend in the grounding wire, a longitudinal pull not only must overcome the frictional engagement of the hinge bearings with the grounding wire, but also must overcome the internal resistance within the wire, due to its having to be continually bent, as the wire tends to be withdrawn from

between the arcuate hinge bearings. The arcuately shaped hinge bearings, therefore, utilize a double action to resist the wire from being withdrawn from between the hinge bearings and 5 hence effectively retain the grounding wire clamped therebetween.

Various modifications in structure, as well as changes in mode of operation, assembly and disposition of the elements, ordinarily occur to those 10 skilled in the art after benefiting from the invention described and taught herein, and so it will be understood that this disclosure is merely illustrative of the preferred form or forms of the invention.

15 What is claimed is:

1. A grounding fitting for a grounding wire comprising a pair of clamping members, a hinge bearing upon each clamping member which hinge bearings are opposed to each other so that a 20 grounding wire received therebetween is engaged on directly opposite surfaces thereof, at least one hinge bearing being a groove facing towards the other hinge bearing which groove is adapted to receive a wire to be grounded, clamping seats 25 upon the clamping members between which a metallic conductor is adapted to be clamped, operating means at one end of the clamping members to force the same together to grip the metallic conductor between the clamping seats and 30 grip the grounding wire between the hinge bearings and within the groove, and a second operating means at the other end of the clamping members to increase the grip on the grounding wire.

2. A grounding fitting for a grounding wire comprising a pair of clamping members, a hinge bearing upon each clamping member which hinge bearings are opposed to each other so that a 40 grounding wire received therebetween is engaged on directly opposite surfaces thereof, at least one hinge bearing being a groove facing towards the other hinge bearing which groove is adapted to receive a wire to be grounded, clamping seats upon the clamping members between which a metallic conductor is adapted to be clamped, an 45 operating screw engaging an end of each clamping member adjacent the clamping seats to force the same together to grip the metallic conductor herebetween and grip the grounding wire be- 50 tween the hinge bearings and within the groove,

and a second operating screw engaging an end of each clamping member adjacent the hinge bearings to increase the clamping grip on the grounding wire.

3. A grounding fitting for a grounding wire 5 comprising a pair of clamping members, a hinge bearing upon each clamping member which hinge bearings are opposed to each other so that a grounding wire received therebetween is engaged on directly opposite surfaces thereof, the hinge 10 bearings being bulged in the same direction to provide substantially parallel bearing surfaces, at least one hinge bearing being a groove facing towards the other hinge bearing which groove is adapted to receive a wire to be grounded, 15 clamping seats upon the clamping members between which a metallic conductor is adapted to be clamped, operating means to force the clamping members together to grip the metallic conductor between the clamping seats and grip the 20 grounding wire between the hinge bearings and within the groove, and a second operating screw engaging an end of each clamping member adjacent to the hinge bearings to assist the first 25 operating means in bending the grounding wire to conform to the bulged hinge bearings.

4. A grounding fitting for a grounding wire comprising a pair of clamping members, a hinge bearing upon each clamping member which hinge bearings are opposed to each other so that a 30 grounding wire received therebetween is engaged on directly opposite surfaces thereof, the hinge bearings being arcuate in a direction axially with respect to the hinge bearings, at least one hinge bearing being a groove facing towards the other hinge bearing which groove is adapted to receive a wire to be grounded, clamping seats upon the clamping members between which a metallic conductor is adapted to be clamped, operating means 35 engaging the clamping members adjacent the 40 clamping seats to force the same together to grip the metallic conductor between the clamping seats and grip the grounding wire between the hinge bearings and within the groove, and a second operating means engaging the clamping members adjacent the hinge bearings to curve 45 the grounding wire between the arcuate hinge bearings and increase the clamping grip upon the wire.
